UNITED STATES PATENT OFFICE.

LAWRENCE C. STEELE, OF PITTSBURGH, PENNSYLVANIA.

OPENER FOR SHEET-METAL PACKS.

Application filed October 11, 1922. Serial No. 593,799.

To all whom it may concern:

Be it known that I, LAWRENCE C. STEELE, a citizen of the United States, and resident of Pittsburgh, in the county of Allegheny,

5 and State of Pennsylvania, have invented a new and useful Improvement in Openers for Sheet-Metal Packs; and I do hereby declare the following to be a full, clear, and exact description thereof.

10 My invention relates to mechanism for opening sheet-metal packs.

In the manufacture of sheet-metal, the first step in the operation is the reducing of the sheet-bar to a sheet by passing it back

15 and forth through suitable rolls, and when the bar has been reduced to a sheet of proper thickness the sheet is then doubled and re-heated, whereupon it is again passed through the rolls in its doubled form, and

20 after being reduced further is redoubled, and this course is followed until the sheet is reduced to the proper gauge, the pack, as it is termed, sometimes containing eight or more sheets. Due to the heat and the

25 pressure given the pack in the rolls, the individual sheets adhere to each other, and the pack has to be opened and the sheets separated, which, because done by hand in most plants, has been a very laborious and

30 expensive operation. In the hand method, in order to open up the pack at one corner so that the sheets become slightly separated, it is necessary to bend the pack at one corner quite abruptly, whereupon the operator,

35 with a leather glove or protector provided with a prong, separates the sheets by inserting the prong between the sheets and prying them apart. This abrupt bend which was given to the corner of the sheet

40 disfigured the sheets at the corner and made defective sheets, so that it was sometimes necessary to cut off the ends of the sheet, which was wasted.

The object of my invention is to provide 45 a machine for opening the packs, which is more satisfactory than those heretofore employed and by which the metal is not bent or distorted in a manner as to injure the sheets, and to do away with the hand labor heretofore employed which made it a very tedious and expensive operation.

In the accompanying drawings, Fig. 1 is a plan view of my improved mechanism; Fig. 2 is a front view on a reduced scale; 55 Fig. 3 is an enlarged detail plan view,

partly in section; and Fig. 4 is an enlarged vertical elevation of the reciprocating members partly in section and partly broken away.

In the drawing the numeral 2 designates 60 a suitable frame on which is mounted the motor 3, the motor-shaft 4 having the worm 5 which meshes with the worm-wheel 6 mounted on the shaft 7 journaled in suitable bearings 8. A bevel-gear 9 on the 65 shaft 7 meshes with the bevel-gear 10 on the shaft 11.

Mounted on the shaft 7 is the crank-arm 12. A pitman or reciprocating member 13 is connected to the crank 12, and in order to 70 vary the throw of said pitman as may be desired the crank is provided with a number of openings 14. The reciprocating member 13 has the extension 15 which projects up through the opening 16 in the plat- 75 form 17 carried by the frame 2.

The extension 15 has the recess or seat 18 formed therein adapted to receive the sheet-opener which consists of a metal bar 19 with corrugated or roughened faces 20. 80 This bar is held in the recess 18 by the clip 21 at the upper end, and at the lower end by the clip 22. The bar 19 is roughened on opposite sides so that when one side becomes worn out the bar may be reversed to 85 present a new roughened or corrugated face.

In the rear of the extension 15 is the friction-roller 23 which is adapted to bear against the rear face of said extension 15 when the device is in operation, and said 90 roller is mounted in the yoke 24 which is connected to the rod 25. The rod 25 passes through the bearings 26 and 27, and a spring 28 is interposed between the bearing 27 and a collar 29 on said rod 25, said 95 spring acting normally to advance the roller 23 into contact with the rear face of the extension 15. In this manner provision is made for the yielding of the extension 15 and the roughened bar 19 carried thereby. 100

There are two of these reciprocating members, and as they are both constructed alike the description of one will apply to the other.

A diagonally arranged guide-bar 30 is 105 secured to the table 17, said guide-bar in conjunction with the said table acting to hold the pack properly in position and prevent its being moved upwardly off the table when the opening operation is taking place, 110

the space between the lower face of said guide-bar and the upper face of the table being just sufficient to conveniently admit the pack to be opened, as clearly indicated in Fig. 4

- A stop 31 is provided, said stop being secured to the lower face of the table 17 and acting to limit the movement of the upper ends of the reciprocating members when 10 no pack is in position to be opened, and said stop has the beveled faces 32, so that when no pack is in position to be opened and the movable members lean toward said stop, the roughened bars 19 will bear only at one edge 15 against the stop and consequently will relieve the wear on the face of the bar when no pack is in position to be opened, and when one pack is being withdrawn for the insertion of another pack.
- 20 The cranks 12 are so set with reference to each other that when one of the reciprocable members is moving upwardly the other one will be moving downwardly, the purpose of which will more fully hereinafter appear.
- 25 When a pack is to be opened, the pack is moved along the table 17 in the guide 30 and into the position indicated in Fig. 4. As clearly shown in Fig. 4, when one of the reciprocating members is moving upwardly, 30 as indicated in full lines in said figure, it will move up at such an angle as to have the roughened bar 19 engage the upper half of the edge of the pack, which will act to separate or loosen the sheets, and on the 35 downward movement, as indicated by the dotted lines in said figure, the angle of the reciprocating member is changed so that the roughened bar 19 will engage the lower half of the edge of the pack and separate 40 the sheets in the lower half of the pack. The pressure with which the roughened bar 19 bears against the edge of the pack is controlled by the strength of the spring 28, and this is so regulated that any undue pressure will be at once relieved, and all unnecessary strain avoided.

As the reciprocating members are working at right angles to each other, said members are moving in opposite directions, and 50 it will be apparent that when one member is working on the upper half of the pack the other member will be working on the lower half of the pack at right angles thereto. The movement of the roughened bar 19 over 55 the edges of the pack in this manner will act to separate the sheets, and the sheets will be so distinctly separated that they may be readily grasped and pulled apart, thereby doing away with the abrupt bending of the 60 pack at the corner and the separating by hand of each sheet with the leather glove and prong, as above referred to.

It is apparent that the number and sizes of the reciprocating members may be varied to suit conditions.

What I claim is:

1. In mechanism for opening packs of sheet metal, the combination of a reciprocating member having a roughened face, and means for reciprocating said member while 75 in contact with the edge of said pack.

2. In mechanism for opening packs of sheet-metal, the combination of a reciprocating member having a roughened face and means for changing the angle of movement 75 of said member, whereby the upper portion of the edge of the pack is engaged on one stroke of said member and the lower portion on the other stroke.

3. In mechanism for opening packs of sheet metal, the combination of a pair of reciprocating members having roughened faces arranged at right angles to each other, and means for moving said members in opposite directions while engaging the edges of 85 said pack.

4. In mechanism for opening packs of sheet-metal, the combination of a pair of reciprocating members having roughened faces arranged at right angles to each other 90 and moving in opposite directions, and means for changing the angle of movement of said members, whereby the upper portion of the edge of the pack is engaged on one stroke of one of said members, and the lower 95 portion on the stroke of the other of said members.

5. In mechanism for opening packs of sheet-metal, the combination of a reciprocating member having a roughened face and 100 yieldingly mounted, and means for reciprocating said member across the edge of a pack, while in contact therewith.

6. In mechanism for opening packs of sheet-metal, the combination of a reciprocating member having a roughened face and yieldingly mounted, and means for changing the angle of movement of said member, whereby the upper portion of the edge of the pack is engaged on one stroke 110 of said member, and the lower portion on the other stroke.

7. In mechanism for opening packs of sheet metal, the combination of a shaft, a crank on said shaft, a reciprocating member having a roughened face connected to said crank, a stop engaging the rear face of said member, whereby when the pack is advanced into the path of said member said member will be brought into engagement with said stop.

8. In mechanism for opening packs of sheet-metal, the combination of a shaft, a crank on said shaft, a reciprocating member having a roughened face connected to said crank, a stop engaging the rear face of said member, whereby when the pack is advanced into the path of said member, said member will be brought in engagement with said stop, and whereby the upper portion of the 120

edge of the pack is engaged on one stroke of said member and the lower portion on the other stroke.

9. In mechanism for opening packs of sheet metal, the combination of a shaft, a crank on said shaft, a reciprocating member having a roughened face connected to said crank, a yielding stop engaging the rear face of said member, whereby when the pack is advanced into the path of said member said member will be brought into engagement with said stop.

10. In mechanism for opening packs of sheet-metal, the combination of a shaft, a crank on said shaft, a reciprocating member having a roughened face connected to said crank, a yielding stop engaging the rear face of said member, whereby when the pack is advanced into the path of said member, said member will be brought in engagement with said stop, and whereby the upper portion of the edge of the pack is engaged on one stroke of said member and the lower portion on the other stroke.

11. In mechanism for opening packs of sheet-metal, the combination of a shaft, a crank on said shaft, a reciprocating member having a roughened face connected to said crank, a roller engaging the rear face of said reciprocable member, whereby when the pack is advanced into the path of said member, said member will be brought in engagement with said roller, and whereby the upper portion of the edge of the pack is engaged on one stroke of said member and the lower portion on the other stroke.

12. In mechanism for opening packs of sheet metal, the combination of a reciprocating member having a roughened face, means for reciprocating said member, and a stop in the path of the forward movement of said member.

13. In mechanism for opening packs of sheet metal, the combination of a reciprocating member having a roughened face, means for changing the angle of movement of said member, whereby the upper portion of the edge of the pack is engaged on one stroke of said member, and the lower portion on the other stroke, and a stop in the path of the forward movement of said member.

14. In mechanism for opening packs of sheet metal, the combination of a reciprocating member having a roughened face, means for reciprocating said member, and a stop having a beveled face in the path of the forward movement of said member.

15. In mechanism for opening packs of sheet metal, the combination of a reciprocating member having a roughened face, means for changing the angle of movement of said member, whereby the upper portion of the edge of the pack is engaged on one stroke of said member and the lower portion on the other stroke, and a stop having a beveled face in the path of the forward movement of said member.

16. In mechanism for opening packs of sheet metal, the combination of a pair of reciprocating members having roughened faces arranged at right angles to each other and moving in opposite directions, means for changing the angle of movement of said members, whereby the upper portion of the edge of the pack is engaged on one stroke of one of said members, and the lower portion on the stroke of the other of said members, and a stop in the path of forward movement of said members to prevent interference.

17. In mechanism for opening packs of sheet metal, the combination of a suitable platform, a guide spaced above said platform to permit of the passage of a pack between said table and said guide, a reciprocating member having a roughened face adapted to engage the edge of the pack, and means for reciprocating said member.

18. In mechanism for opening packs of sheet metal, the combination of a suitable platform, a guide spaced above said platform to permit of the passage of the pack between said table and said guide, a reciprocating member having a roughened face, and means for changing the angle of movement of said reciprocating member, whereby the upper portion of the edge of the pack is engaged on one stroke of said member, and the lower portion on the other stroke.

In testimony whereof I, the said LAWRENCE C. STEELE, have hereunto set my hand.
LAWRENCE C. STEELE.
